UNITED STATES PATENT OFFICE.

PAUL JANZ, OF ST. LOUIS, MISSOURI.

CORN AND CALLOUS RAZOR.

Application filed August 20, 1924. Serial No. 733,160.

To all whom it may concern:

Be it known that I, PAUL JANZ, a citizen of the United States, residing at St. Louis, in the State of Missouri, have invented certain new and useful Improvements in Corn and Callous Razors, of which the following is a specification.

This invention relates to the class of cutlery and pertains particularly to the class 10 of corn and callous razors.

The primary object of this invention is the provision, in a manner as hereinafter set forth, of a corn and callous razor of improved design, and which will act to safely 15 and cleanly shave off light thin patches of callous or corn.

The invention has for another of its objects the provision, in a manner as herein-after set forth, of an improved corn and 20 callous razor so constructed that the affixing of the handle to the head thereof, will securely and positively clamp a razor or cutting blade in position for use and hold the same against any movement.

25 A still further object of this invention is the provision, in a manner as hereinafter set forth, of a corn and callous razor constructed along the lines of the well known safety razor, and having the head thereof formed 30 of a single body of material possessed of an inherent means whereby upon loosening the handle from connection therewith, the head will tend to spring open to release the blade carried thereby.

35 A further and final object of the invention is the provision, in a manner as herein-after to be set forth, of a corn and callous razor of neat and attractive design, capable of being kept clean and sanitary, strong, 40 durable, and inexpensive to manufacture.

The invention will be best understood from a consideration of the following detail description taken in connection with the accompanying drawings forming a part 45 of this specification, with the understanding that the invention is not confined to any strict conformity with the showing of the drawings but may be changed and modified so long as such changes and modifications 50 mark no material departure from the salient features of the invention as expressed in the appended claims.

In the drawings:

Figure 1 is a view of the device embodying this invention showing the application and use thereof.

Figure 2 is a front elevation of the upper portion of the handle and the head of the razor, a portion thereof being broken away to show a detail of construction. 60

Figure 3 is an enlarged side elevation of the device, the head of which is shown in transverse section.

Figure 4 shows the stamped blank from which the head of the razor is formed, the 65 same being in condition to be folded upon itself to provide the finished head.

Figure 5 is an edge view of the blank disclosed in Figure 4.

Referring now to the drawings in detail 70 wherein like numerals of reference indicate corresponding parts throughout the several views, the description will begin with the formation of the blank as shown in Figure 4.

75 As shown in this figure a rectangular piece of metal, indicated as a whole by the numeral 1, is provided, and there is pressed into this blank piece of metal the transverse groove 2 which is adjacent one end so thereof as shown.

Through the longitudinal center of this blank and of the groove, there is formed the aperture 3 which is threaded. That portion of the blank lying between the groove 85 3 and the adjacent parallel edge, comprises, when the blank is bent to provide the finished head, the top guard or shield 4 of the razor. A second circular aperture 5 is formed through the longitudinal center of the blank 1 as shown, and between this aperture and the adjacent end of the blank there is cut through the blank the transversely extending elongated opening 6. The inner longitudinal edge of the metal 95 through which this opening is formed is turned upwardly as at 7, while the outer longitudinal edge is pressed down forming what might be termed a chute 8.

The end edge of the blank adjacent the 100 downturned edge of the opening 6 is bent downwardly to form the transverse lip 9 while the bent portion of the lip 9 at each side edge of the blank is forced upwardly a slight distance to provide the spaced raised 105 portions 10 which constitute edge guards for each end edge of the razor blade which is used in connection with the head, in the manner to be hereinafter described. There is thus formed at the central portion of the 110 flanged edge 9 between the raised portions 10, the opening or passage 11.

When the blank has been formed in the manner as above set forth, the same is ready to be bent to form the completed head of the razor. In finishing the head the guard portion 4 together with the grooved portion 2, is bent over and superposing the guard portions upon that portion of the blank through which the opening 6 is formed. In other words, the blank is bent at its central portion at 12, and the edge 13 of the guard portion 4 is located above and substantially parallel with the lowermost edge of the downturned edge of the so called chute 8. The head now formed has the cross-sectional appearance shown in Figure 3, and the portion at which the blank is bent is substantially circular and forms the rolled spring back 12^a which is shown in Figure 3.

It is preferred to use that type of razor blade which has a back or rib across one edge, and when the same is used, when the blade is in position between the top guard 4 and the underside or the bottom of the head 14, the upwardly pressed central portion 7 will bear against the body of the blade 15 and the back 16 of the blade will bear against one downturned portion of the groove 2 and will be positioned between the top 4 and the bottom 14, as shown. The edge of the blade adjacent each side thereof, will be pressed against the inner side of the guards 10 whereas the central portion of the blade, indicated at 17, will extend across the open central portion 11 and across the opening 6 in the bottom 14.

There is now provided a handle 18 of any appropriate design having at its upper end the threaded stud or post 19 which is adapted to pass freely through the lower aperture 5 of the head and threadedly engaged in the upper aperture 3 which is formed in the groove 2. The shoulder 20 of the handle will abut the underside of the head of the razor, and as the stud 19 is threaded through the aperture 3 it will draw the top part of the razor head downwardly thus securely clamping the blade 15 in position between the top guard and the bottom 14, thereby preventing the same from moving in any direction.

From the foregoing description it will be seen that there has been provided a razor of unique design, and of such construction as to permit it to be freely used without danger of cutting too deeply into the corn or callous to which it is applied.

Having thus described my invention what I claim is:

1. In a razor of the character set forth, a head comprising a top blade guard portion and a bottom blade supporting portion, said bottom portion having a transversely disposed aperture cut therethrough having the forward edge thereof bent downwardly and the rear edge bent upwardly to engage the

underside of, and flex a cutting blade when positioned within the head, means to provide a guard for each end of the cutting edge of a blade, and a handle member having a portion thereof extending between and connecting said top and bottom portions. 70

2. In a razor of the character set forth, a head comprising a top blade guard portion, a bottom blade supporting portion, and an intermediate connecting rolled portion 75 having inherent means to set up a resilient connection between the said top and bottom portions, said bottom portion having a transversely disposed aperture cut therethrough having the forward edge thereof bent downwardly and the rear edge bent upwardly to engage the underside of, and flex, a cutting blade when positioned within the head, means to provide a guard for each end of the cutting edge of a blade, and a handle member having a portion thereof extending between and connecting said top and bottom portions. 80

3. In an instrument of the character set forth, a blade carrying head comprising a body of material bent upon itself to provide a top blade guard and a bottom blade support, said blade support being formed to provide a central through opening for the passage of severed material and a blade edge guard at each end of the opening, and a handle member removably secured to said head. 85

4. In an instrument of the character set forth, a blade carrying head comprising a body of material bent upon itself to provide a top blade guard and a bottom blade support, said blade support being formed to provide a central through opening for the passage of severed material and a blade 100 edge guard at each end of the opening, and a handle member removably secured to said head, said handle member, when engaged with said head, acting to draw the top and bottom parts thereof together. 105

5. In an instrument of the character set forth, a blade carrying head comprising a body of material bent upon itself to provide a top blade guard and a bottom blade support, said blade support being formed to 110 provide a central through opening for the passage of severed material and a blade edge guard at each end of the opening, and a handle member removably secured to said head, said handle member, when engaged with said head, acting to draw the top and bottom parts thereof together, and said head possessing an inherent quality whereby it will be caused to open sufficiently, upon removal of said handle, to allow easy insertion 115 or removal of a cutting blade. 120

6. In an instrument of the character set forth, a blade head comprising a body of material bent upon itself to provide a top blade guard and a bottom blade support, 125

said blade support being formed to provide a central through opening for the passage of severed material and a blade edge guard at each end of the opening, and a handle member removably secured to said head, one edge of said opening being struck upwardly to engage the under side of a cutting blade

clamped between the guard and support, to cause the same to be slightly flexed to improve the action of the instrument.

10

In testimony whereof, I affix my signature hereto.

PAUL JANZ.
